PULSE GENERATION DEVICE

Loring C. White, Reading, Mass., assignor, by mesne assignments, to Sylvania Electric Products Inc., Wilmington, Del., a corporation of Delaware

Application December 8, 1955, Serial No. 551,789

7 Claims. (Cl. 313—73)

This invention relates to vacuum electron discharge devices, and more particularly to discharge tubes having a plurality of discharge gaps arranged in a magnetic field and adapted to produce output pulses at an array of target or collector electrodes.

From the following more detailed description of the tubes of my invention certain similarities of these tubes to known types of so-called "switching tubes" will be noted. Such switching tubes commonly have been employed in pulse counting and pulse distributing applications in which the electron discharge in a multi-gap tube is caused to shift from one gap to a second gap by application of a pulse applied to a control or grid electrode associated with the target or collector electrode of the second gap. Thus progression of the discharges to produce pulses in an external circuit or circuits is accomplished with the aid of a pattern of input pulses to grid or control electrodes. In contrast to these known tubes, the pulse generating tubes of my invention are adapted to produce at the output a succession of pulses without the aid of such input controlling pulses. Attempts also have been made to adapt these known types of counting tubes for pulse generation. However, these attempts have been accompanied either by the necessity for additional tube elements, and resulting complicated circuitry, or by an inherent inflexibility of such devices with respect to maximum frequencies and ranges of operable frequencies.

It is therefore an object of this invention to provide a pulse generating tube which is not dependent for frequency control on a supply of pulsed energy to the tube.

A further object is to provide a pulse generating tube operable over a wide range of frequencies.

A still further object is to provide a pulse generating tube having a plurality of electron discharge gaps in which transfer of a discharge from each gap to an adjacent gap is accomplished rapidly and positively by virtue of a novel configuration and arrangement of electrode elements within the tube.

The foregoing objects are realized in tubes of this invention which may be described generally as including a heated cathode centrally located within an evacuated envelope, which cathode constitutes a common electrode for a plurality of electron discharge gaps. A generally circular array of anodes is located radially outward from the cathode. These anodes serve as collector electrodes or targets for the discharge gaps. A magnetic field through the evacuated enclosure perpendicular to the array of discharge gaps is provided by a magnet structure appropriately arranged with respect to the tube envelope. Associated with each collector electrode is a beam forming or transfer electrode, these latter electrodes forming an array radially outward from the cathode, each one having at least a portion of its structure closer to the cathode than any portion of its associated collector. An important feature of the present invention includes particular characteristics of the structures of these beam forming electrodes.

To facilitate explanation of the design and operation of my pulse generating tube it may be stated that cer-

2

tain principles of operation of known types of counting or switching tubes are also involved in the present tube. Thus, the interaction of the magnetic field through the discharge gaps and the electrical field established by a potential difference maintained between the cathode and the arrays of beam forming and collector electrodes results in the production of an electron beam within the tube. The beam may be directed into a path moving toward any individual collector as a result of changes in the electric field within the tube. For example, in counter tubes of known types employing this principle of operation, the discharge may be directed first toward one target or collector electrode and subsequently, at predetermined intervals, toward other electrodes in an array by application of voltage pulses from an external source successively to the other electrodes. As previously noted in the description of the tubes herein described, the application of externally applied control pulses is not employed, and in this respect the parallelism ceases between the principles of operation of the previously known counter tubes and my novel pulse generating device. More particularly, the changes in the electric field in my tube, essential to the transfer or "stepping" of the discharge in rotating fashion about the cathode results from the novel configuration of the beam forming electrodes and the arrangement of those electrodes relative to the cathode and the target or collector electrodes. As will be obvious from the subsequent more detailed description of these elements of the device, each of the beam forming electrodes includes electron intercepting structure extending into the discharge zone between the cathode and the adjacent target or collector associated with an adjacent beam forming electrode, this zone being coextensive with the space within the envelope occupied by the electron beam at the time of discharge at the gap defined by the cathode and the collector.

In operation, the electron intercepting structure of a particular beam forming electrode picks up a portion of the electrons in the discharge zone of the adjacent gap upon the occurrence of the beam at that gap. The flow of electrons to the beam forming electrode via the electron intercepting structure is effective to cause the potential of the beam forming electrode rapidly to approach that of the cathode. Simultaneously the potentials of the preceding adjacent beam forming electrode and associated target or collector tend to increase relative to the cathode by virtue of the extraction of the electrons from their discharge gap. In this way the potential distribution in the electric field is altered to establish a new path for the electron beam in the discharge zone between the cathode and target or collector associated with the aforementioned particular beam forming electrode. Once started in the manner hereinafter set forth, this beam transfer or switching action continues sequentially around all the positions defined by the arrays of beam forming and collector electrodes, the action taking place at a rate determined by the strength of the magnetic field, the spacing of the electrodes, and the external circuitry.

60 In the drawings:

Fig. 1 is a perspective view of a preferred embodiment of my invention with portions of the magnet, surrounding envelope, and supporting structure removed.

Fig. 2 is a cross-sectional view of the device of Fig. 1 through 2—2.

Fig. 3 is an enlarged plan view of the electrode structure in the device of Figs. 1 and 2.

Fig. 4 is an enlarged plan view of a modified electrode arrangement.

Fig. 5 is a typical circuit employing a sixteen element tube as a sixteen output pulse generator.

The preferred embodiment of my invention as disclosed in Figs. 1, 2 and 3 comprises a glass envelope 1 having a base 2 wherein conductive leads 3 leading from the elements within the envelope are sealed and made available for connecting to the external circuitry through external terminals as shown. The envelope is evacuated and contains insulating mica discs 4 and 5 which support and retain in position the electrodes of the device. Centrally located in the glass envelope is a slim rod-like indirectly heated cathode 6 suitably coated with an electron emissive substance. Sixteen target or collector electrodes 7-22 are arranged in a generally circular array about the cathode. The collector electrodes are metal strips of modified L cross-section, one arm being substantially normal to the radius of the tube, and the other arm extending generally radially toward the cathode. Sixteen beam forming or transfer electrodes 37-52 are located in the annular space between the cathode and the array of collector electrodes. Each transfer electrode is arranged in a particular manner with a respective one of the collector electrodes as hereinafter described.

The beam forming electrodes as shown on an enlarged scale in Fig. 3 include an elongated channel-like portion of generally U-shaped cross-section having sides 46a and 46b and a tip or vertex 46c with the open end overlapping and closely adjacent to the radially directed arm of its associated collector electrode and with its closed end or tip facing toward the cathode. One side or leg of the U-shaped portion is closer to the radial arm of the collector electrode than is the other side as best shown in Fig. 3. In the arrangements shown in Figs. 1, 2 and 3, a vane 46d consisting of a flat metal plate extends along the side of the beam forming electrode which is more closely adjacent its associated collector electrode and toward the center portion of the tube into the discharge zone between the cathode and the adjacent target or collector electrode. This vane may be a separate plate of metal brazed or otherwise conductively secured to the U-shaped portion of the electrode or alternatively may be an integral part of the U-shaped portion sharply bent to the configuration shown. The distance of the tip or leading edge of the vane from the central axis of the tube is of the order of three times the diameter of the cathode. Desirably the cathode should be of relatively small diameter so that no portion of the beam forming electrode is closer to the surface of the cathode than a distance equivalent to about twice the diameter of the cathode.

The beam forming electrodes and the collector electrodes preferably are constructed of a non-magnetic nickel alloy. The glass envelope is surrounded by a cylindrical permanent magnet 60 arranged so as to provide an axial magnetic field which has lines of flux extending upwardly through the tube as indicated by the conventional symbol in Fig. 2.

Under usual operating conditions the beam forming electrodes and the collector electrodes are biased positive with respect to the cathode. The strength and influence of the electric and magnetic fields are such that the electrons move around the cathode, but their path does not extend to the beam forming electrodes, until the potential of one of the beam forming electrodes is lowered, changing the electric field sufficiently to deflect the path of the electron beam outwardly toward the electrode. As some of the electrons strike the beam forming electrode a negative resistance action takes place. Current flowing in the associated circuit of the beam forming electrode causes a potential drop to take place across the resistance of the circuit and thus lowers the potential drop between the beam forming electrode and cathode. This action is cumulative. The lower the potential of the beam forming electrode becomes the more it distorts the electric field and picks up electrons, thus causing more and more current to flow in its circuit and continually increasing the potential drop across the circuit resistance. As the

beam forming electrode approaches cathode potential the entire electron beam, following lines of equal potential, attempts to flow around the beam forming electrode.

Due to the action of the electric and magnetic fields the individual electrons follow a trochoidal path. Some of the electrons strike the beam forming electrode to provide the negative resistance action hereinbefore described. The majority of them, however, tend to move along the vane and then around the beam forming electrode, striking the positively biased collector electrode which is positioned closely adjacent the beam forming electrode, and thence through the collector electrode circuit.

Referring to Fig. 3, and assuming that an electron discharge between cathode 6 and collector electrode 15 has been established as described above, the manner in which the discharge is caused to advance to its next position at electrode 16 will be apparent from the following explanation. The vane portion 46d of beam forming electrode 46, which extends into the discharge zone of collector electrode 15, intercepts electrons from the discharge zone, causing a reduction of the potential of electrode 46. The flow of electrons through the circuit associated with electrode 46 produces the cumulative negative resistance action previously described, which action continues until the potential of electrode 46 is reduced sufficiently to form the discharge with collector electrode 16 as the target. The beam forming electrode 45 returns to its biased potential as the electron flow to it and its associated anode 15 is reduced to zero. The rate at which this cut-off occurs depends on the time constant of the beam forming electrode circuit. The action as described takes place clockwise and sequentially in the array of beam forming electrodes and collector electrodes of the device as indicated by the arrow in Fig. 2. About 90% of the electron current flow is available at the collector taking part in the discharge.

Fig. 5 discloses a typical circuit employing the device of this invention to obtain pulses at sixteen outputs. The tube has sixteen sets of beam forming electrodes 37-52 and collector electrodes 7-22 positioned around the cathode 6. The cathode is indirectly heated and is connected through a resistance 23 of about 1500 ohms to ground. Each collector electrode is connected through a resistance 24-24 of about 3,300 ohms to the positive side of a D.C. source 32 of about 200 volts. An output connection 31 is provided at each collector electrode. Each beam forming electrode is connected through a resistance 25-25 of about 100,000 ohms to the positive side of the D.C. source. A small trimmer capacitor 26-26 is placed across each resistance 25-25 for adjusting the time constant of the beam forming electrode circuit and thus regulating the time lag between output pulses. Normally closed switches 27 and 28 are provided for starting and stopping operation of the circuit. The momentary opening of switch 27 lowers the potential of beam forming electrode 52 and, as previously described, causes it to distort the electric field within the tube with resultant electron flow from the cathode to target electrode 22. Opening of the normally closed switch 28 reduces the potential on all the beam forming electrodes to near cathode potential and cuts off electron flow by eliminating the electric field between the cathode and other elements of the tube. On closing of switch 28 so as to return all beam forming electrodes to bias potential no action occurs because, as previously indicated in this specification, the relative strengths of the electric and magnetic fields are such as to prevent electrons from reaching the beam forming electrodes. Action can be reinitiated only by opening and then closing the switch 27 as described above. Resistances 29 and 30 are of the order of one megohm. The magnetic field is about 400 gauss.

Devices constructed as hereinabove described, and operating in the above circuit have generated pulses at a

rate of over one megacycle per second. The frequency of generated pulses is directly related to the supply voltage and inversely related to the magnetic field strength and the time constants of the individual beam forming electrode circuits.

Fig. 4 depicts a modified form of the beam forming electrode which may be employed in tubes of my invention. The vanes of the channel-like beam forming electrodes in the preferred embodiment hereinbefore described are eliminated, and the electron intercepting function of the vanes is afforded instead by portions 71d and 72d of the sides 71a, 72a of the U-shaped electrodes 71, 72 farthest away from the respective associated collector electrodes 81, 82. This is accomplished, for example, as shown in Fig. 4, in which portion 72d is shown as an extension of one leg 72a of the main portion of the electrode 72, which extension is bent or curved outwardly at a greater angle with the axis of the U cross-section than the angle between the main portion 72a of the side of the U and the axis thereof so that at least the extreme edge of the extension lies within the zone occupied by the path of the electrons moving to target electrode 81 from cathode 86. In a manner corresponding to that described in connection with the vaned electrodes the outwardly bent portion 72d intercepts some of the electrons as they flow to collector electrode 81 to induce shifting of the electron flow to electrode 82.

It also has been found possible to operate the device as a pulse generator with other modifications of the electrodes. For example, it is possible to eliminate the targets and take the outputs from the beam transfer electrode circuits. However, the greatest amount of usable output has been obtained with the preferred embodiment of my invention involving the use of collector electrodes.

With various circuit arrangements a variety of ways of using the tubes of the invention are possible. For example, the number of output positions can be reduced by connecting adjacent beam forming electrodes and targets together and properly changing resistance values. Various combinations of outputs can be made to obtain different pulse sequences on different output channels. Still further, the time between pulses can be varied independently by the amount of capacitance and/or resistance used in the beam forming electrode circuits.

What is claimed is:

1. A pulse generator tube comprising an evacuated envelope enclosing a cathode, a plurality of collector electrodes positioned in a circular array around said cathode, each collector electrode forming an electron discharge zone with said cathode, a plurality of beam forming electrodes of generally U-shaped cross-section each having its open end disposed toward one of said collector electrodes and its vertex disposed toward said cathode, one beam forming electrode positioned intermediate at least a portion of each of said collector electrodes and said cathode, each of said beam forming electrodes having an electron intercepting vane extending along one side of said U-shaped cross-section into the electron discharge zone between an adjacent one of said collector electrodes and said cathode, each of said collector electrodes and beam forming electrodes being insulatingly supported from each other and from said cathode and means for producing an axial magnetic field within said envelope.

2. A pulse generator tube as in claim 1 in which the said vane of each beam forming electrode extends no closer to said cathode than at least twice the diameter of said cathode.

3. A magnetron type multiple position beam switching tube comprising an elongated substantially evacuated envelope, an elongated thermionic cathode centrally disposed therein, a plurality of elongated U-shaped beam-forming electrodes symmetrically arranged in a circular

array around said cathode with the open side of the electrode facing outwardly from the cathode, a like plurality of elongated substantially L-shaped target electrodes symmetrically arranged in a concentric circular array adjacent to said array of beam-forming electrodes and on the side which is more remote from said cathode, one section of the L of each target electrode extending into the space between the outwardly extending portions of an adjacent one of said beam-forming electrodes and lying substantially along a radius of said arrays, the extremity of said one section of the L being closer to one of the outwardly extending portions of its associated beam-forming electrode than to the other, and the other section of the L of each target electrode extending across the space between said one outwardly extending portion of a beam-forming electrode and the other outwardly extending portion of the next adjacent beam-forming electrode and disposed substantially normal to a radius of said arrays, each of said beam-forming electrodes each further including an elongated vane extending inwardly toward said cathode along said one outwardly extending portion.

4. An electron tube for operation under the influence of crossed magnetic and electric fields comprising an elongated substantially evacuated envelope, a thermionic cathode centrally disposed therein, a circular array of similar U-shaped beam-forming electrodes the sides of which extend away from said cathode, a circular array of similar L-shaped target electrodes disposed adjacent to said array of beam-forming electrodes and on the side thereof which is more remote from said cathode, one section of the L of each target electrode being disposed substantially normal to a radius of the tube and forming a beam-receiving surface and the other section extending into the space between the outwardly extending portions of an adjacent one of said beam-forming electrodes and lying substantially along a radius of said arrays, the extremity of said other section of the L being closer to one of the outwardly extending portions of the beam-forming electrode than the other, and a further structural member conductively joined to the said one outwardly extending portion of each of said beam-forming electrodes and extending into the electron discharge zone between an adjacent one of said target electrodes and said cathode.

5. Apparatus in accordance with claim 4 wherein the further structural member is an elongated vane extending inwardly toward said cathode along said one outwardly extending portion of the beam-forming electrode.

6. Apparatus in accordance with claim 5 in which the said vane extends no closer to said cathode than at least twice the diameter of said cathode.

7. Apparatus in accordance with claim 4 wherein the further structural member is an extension of said other outwardly extending portion of the beam-forming electrode, said extension being bent outwardly of the plane of said other portion such that at least a portion thereof lies within the path of electrons moving from said cathode to the target electrode.
